T. MACDERMOTT,
RELEASING GEAR FOR SHIPS' BOATS,
APPLICATION FILED SEPT. 3, 1915.

1,191,447.

Patented July 18, 1916.

INVENTOR:
THOMAS MACDERMOTT
BY: *Frank J. DeGennaro*
ATTORNEY.

UNITED STATES PATENT OFFICE.

THOMAS MACDERMOTT, OF PORTSMOUTH, ENGLAND.

RELEASING-GEAR FOR SHIPS' BOATS.

1,191,447.

Specification of Letters Patent. Patented July 18, 1916.

Application filed September 3, 1915. Serial No. 48,869.

To all whom it may concern:

Be it known that I, THOMAS MACDERMOTT, subject of the King of Great Britain and Ireland, residing at 79 Shadwell road, 5 Portsmouth, in the county of Hampshire, England, have invented new and useful Improvements in Releasing-Gear for Ships' Boats, of which the following is a specification.

10 This invention relates to improvements in releasing gear for ships' boats of that type in which the main or carrying hook is adapted to rotate about a pivot under the action of the load and release the said load, but is 15 retained in position by retaining means having a large mechanical advantage over the said load and has for its object the provision of means whereby great simplicity of construction is obtained and at the same time 20 more reliable operation is assured than occurs with known devices.

The invention consists in the arrangement within a boat and attached to the ends and keel thereof of two devices each of which 25 comprises a pivoted two armed main or carrying hook substantially of U shape. One arm of the said hook is adapted to receive the ring of one of the boat falls while the other arm is engaged by a pivoted retaining hook adapted to be manually operated. 30 The pivots of both the carrying and retaining hooks are so disposed relative to their points of application of load that they will rotate under the action of the load when unrestrained; the retaining hooks releasing 35 the carrying hooks which in turn release the rings of the falls. Both the retaining hooks are adapted to be simultaneously released by a fore and aft cord or rope which is provided with a slip device. To prevent accidental release I provide a safety pin adapted 40 to engage with and lock one of the movable hooks; the said safety pin having to be removed before operation of the device can be effected. I also provide means adapted to 45 mouse the hook and thereby prevent the falls from being accidentally unhooked.

On referring to the drawings:—Figure 1 50 illustrates in elevation a hook constructed according to my invention. Fig. 2 is an elevation similar to Fig. 1 but showing some of the parts in section.

55 Referring to the drawing it will be seen that the U-shaped main or carrying hook A is carried rotatably on a pin A¹ mounted in the side plates A² and that the said hook A is disposed between the said side plates A².

The U-shaped main or carrying hook A is horizontally disposed and has the upper leg A³ thereof curved in order to prevent the ring F of the boat falls slipping off until released; while the lower leg A⁴ is substantially straight and is provided with a hole or slot A⁵ adapted to receive the retaining hook B. The retaining hook B is pivoted on the pin B¹ and is disposed between the side plates A² which carry the said pin B¹. This retaining hook B is somewhat similar to the carrying hook A inasmuch as it is provided with two legs B² and B³, one of which viz:—the leg B² is adapted to engage 60 the hole or slot A⁵ in the main or carrying hook A. The other leg B³ carries a shackle E at its outer end for attachment to the fore and aft cord or rope which is provided with a slip device. By varying the angle of the leg B² relative to the plane of the hole or slot A⁵ I am enabled to increase or decrease 65 the mechanical advantage of the pull on the fore and aft cord or rope over the load.

Upon the parts of the pin B¹ which project beyond the side plates A² I mount an anchoring shackle D which is connected to the inside of the boat at the keel or other convenient point while upon the projecting parts of the pin A¹, I mount a similar 70 shackle C for attachment to the upper part of the stem or stern of the boat as the case may be. To prevent sidewise motion of the boat relative to the hooks side stays are used and to facilitate the attachment of the side 75 stays to the hooks I provide two eyes C¹ one of which may be formed integrally with the pin A¹ and form its head while the other may be in the form of a nut adapted to maintain the pin A¹ in place.

90 In order to mouse the hook and prevent the ring F from becoming detached from the curved upper leg A³ I continue the sides of the shackle D upward beyond the pivot pin B¹ a sufficient distance to enable the ends G of the extensions D¹ to come close enough to the end of the leg A³ to prevent the passage of the ring F therebetween. To prevent deflection of the extensions D¹ under stress I provide a pin X adapted to engage 95 the shackle D and prevent backward motion thereof beyond a predetermined point.

Under normal circumstances it is desirable 100 to maintain the hook in the operative position without the use of a fore and after cord and to effect this I provide a safety pin H 105 which is adapted to engage with the leg B³.

of the hook B and prevent motion thereof for disengaging operation.

In use a fore and aft cord or rope or similar tackle provided with a slip device is attached to the shackles E and hauled tight. The safety pins H are removed, and at the word of command the person in charge of the slip releases it upon which both hooks simultaneously disengage and the boat as a consequence takes the water on an even keel.

I claim:—

A releasing gear for ships' boats having in combination two supporting devices disposed within each boat and adapted to engage the boat falls, each of the said supporting devices being flexibly attached to the keel and one end of the boat and comprising a pivoted main or carrying hook of U-shape adapted to assume a vertical disposition under stress when uncontrolled, a pivoted retaining hook of U-shape adapted to engage with and control the said main or carrying

hook with great mechanical advantage, a fore and aft cord or rope having a manually operable slip device adapted to control said pivoted retaining hooks, permit them to simultaneously release the said carrying hooks in both supporting devices, and act against the pull of the attachment of the supporting device for the end of the boat, a locking pin adapted to engage one of the said hooks and thereby prevent movement of the main or carrying hook when desired and pivoted tongues adapted to mouse the hook the said tongues being formed integrally with the keel anchoring shackle, substantially as described.

In testimony whereof I have signed my name to this specification in the presence of two subscribing witnesses.

THOMAS MacDERMOTT.
